ULTRA-SHORT WAVE AERIALS

Henri Gutton and Antoine Jean Ortusi, Paris, France, assignors to Compagnie Generale de Telegraphie Sans Fil, a corporation of France

Application June 25, 1952, Serial No. 295,384

Claims priority, application France July 3, 1951

3 Claims. (Cl. 343—783)

This invention relates to ultra-short wave aerials. 15 Radio aerial systems suitable for use on ultra-high radio frequencies, and having one of the two perpendicular dimensions very different from the other, are of course well known. A typical example of such a known aerial system is the so-called "cheese" aerial, commonly employed for radar and which comprises a cylindro-parabolic reflector of small height, but much greater width, fed by a small horn ending a wave guide.

In practice the cylindrical height of a cheese aerial must be greater than half a wavelength. In many cases, however, it would be advantageous to be able to reduce this dimension below the half wavelength, as for example in the case of an aerial for mounting on a very high speed vehicle such as a fast aeroplane.

The present invention seeks to provide improved aerials wherein one dimension may be made extremely small but which will nevertheless provide a radiation diagram comparable with those of known aerials of considerably larger dimensions.

According to the invention, an aerial is constituted by a wave guide, one wall of which is extended in the axial direction by a substantially flat metal plate which is covered with a substantially uniform layer of dielectric material which also penetrates into a part of the wave guide where its thickness diminishes progressively. With a rectangular guide the plate extension is preferably trapezoidal with the shorter of its two parallel edges common with one of the longer edges of the guide mouth. The layer of dielectric outside the guide is preferably pierced with holes suitably disposed and having suitable diameters to maintain the wave front plane at the outlet of the plate.

The invention is illustrated in the accompanying drawings which show schematically one embodiment, Figure 1 showing the aerial as a whole and part of the wave guide, and Figure 2 showing a detail of the dielectric plate.

Referring to Figure 1, a wave guide 1 has its bottom wall extended by a flat plate 2 made of a metal of good electrical conductivity. The extension is of trapezoidal shape and is covered with a substantially uniform layer 3 of dielectric material the thickness of which is indicated at *a*.

If ϵ is the dielectric constant of the material of the layer 3, a wave coming along the guide in the direction of the arrow A will continue to be propagated in the direction Oz at the guide outlet if the thickness *a* is greater than a minimum value

$$a_0 = \frac{\pi}{2K\sqrt{\epsilon-1}}$$

where *K* is the constant of propagation in the undefined space (beyond the guide mouth) and is given by the relation

$$K = \frac{2\pi}{\lambda}$$

2

where λ is the wavelength. If the value of *K* is substituted in the above equation, it becomes:

$$a_0 = \frac{\lambda}{4\sqrt{\epsilon-1}}$$

If *a* is raised from the value *a*₀ the theoretical limit of infinity, the speed of propagation rises from *K* to $\sqrt{\epsilon}K$.

The plane xOy constitutes a radiating mouth along which the wave has a constant phase. From a study of the radiation diagram in the plane of symmetry yOz, it may be shown that the field at any point M is a function of the angle

$$\theta = \widehat{zOM}$$

The radiation diagram is symmetrical around Oz and the width of the diagram at half-power is a function of the thickness of the dielectric *a* and of its constant ϵ .

In order to avoid excessive losses in the dielectric, the latter is preferably made of a thickness between *a*₀ and 1.4 *a*₀ (*a*₀ having the value defined above). In these conditions it is found, for a value of ϵ equal to 2, the radiation diagram at half-power forms an angle of about 45°.

If it is desired to reduce the width of this diagram, the thickness of the dielectric is given a value closer to *a*₀. For *a*=*a*₀, the wave slides along the dielectric, no energy penetrates (theoretically) into the latter and there is no radiation properly speaking, no distinction being made between the initial wave and the diffracted wave.

Thus, by suitably selecting the thickness *a* and the constant ϵ of the dielectric, it is possible to obtain in the vertical plane (plane yOz) a diagram having the desired width. The diagram in the horizontal direction (plane xOz) is defined by the length of the plate 3 along Oz, and it may be made as fine as desired.

The dielectric layer 3 is extended by a bevelled tongue 4, which progressively transforms a H₀₁ wave in the guide into a wave propagated at the speed of light in the space beyond the guide mouth.

If the wave guide is disposed on a metal surface, for example, the outer shell of an aircraft wing, the dielectric layer may be disposed directly on said surface.

In order to obtain at the outlet end of the dielectric a wave front perpendicular to the axis of the guide, it is necessary to compensate for the different effective lengths in the different directions in relation to the axis direction. For this purpose the dielectric layer is pierced with holes having vertical axes and disposed in such manner as to advance the wave in the direction under consideration. The diameters of the holes, which are smaller than one-quarter of the wavelength in the dielectric, vary according to the direction, the size of the holes increasing for directions more and more inclined to the axis of symmetry of the whole arrangement. Figure 2 illustrates one example of such perforation.

We claim:

1. An ultra-short wave antenna comprising an elongated tubular wave guide having a substantially uniform rectangular cross section along its axis; a flat metal plate extending from one wall of said wave guide in direction of the axis of said wave guide and having a width substantially larger than the thickness thereof; a substantially uniform layer of dielectric material covering said flat metal plate and penetrating into a portion of said wave guide in which its thickness diminishes progressively, the width of said layer being substantially larger than the thickness thereof.

2. An ultra-short wave antenna comprising an elongated tubular wave guide having a substantially uniform rectangular cross section along its axis; a flat metal plate extending from one wall of said wave guide in direction

of the axis of said wave guide and having a width substantially larger than the thickness thereof; a substantially uniform layer of dielectric material covering said flat metal plate and penetrating into a portion of said wave guide in which its thickness diminishes progressively, the width of said layer being substantially larger than the thickness thereof, said layer of dielectric material outside said wave guide being formed with holes having their axes perpendicular to the surface of said dielectric layer, said holes being disposed and dimensioned to maintain a planar wave front at the outlet of said plate.

3. An ultra-short wave antenna comprising an elongated tubular rectangular wave guide having a substantially uniform cross section along its axis; a trapezoidal shaped large flat metal plate extending from one of the edges of said tubular rectangular wave guide, the smaller parallel side of said trapezoidal shaped metal plate being common with said one of the edges of said tubular rectangular wave guide; a substantially uniform layer of dielectric material covering said flat metal plate and penetrating into a portion of said wave guide in which its thickness progressively diminishes; the portion of said

4
dielectric layer located outside said wave guide having a thickness comprised between

$$\frac{\lambda}{4\sqrt{\epsilon-1}} \text{ and } \frac{1, 4\lambda}{4\sqrt{\epsilon-1}}$$

where λ is the wavelength of the radiated wave, and ϵ the dielectric constant of said dielectric material.
